UNITED STATES PATENT OFFICE.

EDWIN W. M. BAILEY, OF AMESBURY, MASSACHUSETTS.

METAL WINDOW-GLASS CUSHION.

Application filed September 20, 1923. Serial No. 663,807.

To all whom it may concern:

Be it known that I, EDWIN W. M. BAILEY, a citizen of the United States, a resident of Amesbury, in the county of Essex and Commonwealth of Massachusetts, have invented an Improvement in Metal Window-Glass Cushions, of which the following is a specification.

In the construction of closed bodies for automobiles, it is customary to provide the windows with vertically sliding glass plates which are guided at their side edges by means of ways or channels secured in the casing, metal devices for this purpose being shown in my prior Patent #1,374,629.

While the devices therein shown are satisfactory for the purpose of guiding and holding the glass so that it will be protected against the shock of a vehicle body, it has been found desirable to provide some cushioning means for the top edge of the glass when in raised or closed position, where the raising and lowering means are applied to the lower end of the glass, as is customary, and the glass is raised to close the window opening.

Prior to my invention, when a cushioning means has been employed for the upper edge of the glass, it has been found unsatisfactory for several reasons, for example:—when rubber is employed, it loses its life in about two years, while felt becomes worn and is liable to become torn or displaced, particularly where the edge portion of the glass is forced between two felt surfaces.

It is desirable that a device for this purpose shall provide a cushioning seat for the glass vertically, a cushioning support at each side thereof, and a construction which will permit the ready entrance of the glass between the lateral cushioning supports into engagement with the cushioning seat.

The objects of my invention are to provide a cushioning means for the upper edge portion of the glass which shall not only perform the functions above referred to, but which also may be made of metal at small expense, which will readily receive the end edge of the glass plate, even if the glass is somewhat imperfectly guided at its side edges, which will provide a seat for said upper edge which will afford a gradually increased resistance to the closing movement and a resilient or yieldable abutment which will become operative at the end of

such movement, so as to prevent undue strain on the closing means, and which, when the glass is in closed position, will effectively cushion the same laterally.

I accomplish these objects by providing a strip of resilient sheet metal which is bent into an approximately U-form and has its side portions provided with inwardly turned, convergently disposed cushioning end portions which are arranged to engage the end edge of the glass plate and be wedged apart in advance of its reaching the highest point in its movement and to engage one or both more positively at the point at which the upward movement should be arrested.

For a more complete disclosure of my invention, reference is made to the accompanying drawing in which:

Fig. 1 is a combined cross-sectional and perspective view of a window casing, showing a preferred embodiment of my invention.

Fig. 2 is a longitudinal sectional view of the form of cushioning device shown in Fig. 1.

Fig. 3 is a transverse section of the casing, showing the window glass in a lowered position.

Figs. 4, 5 and 6 are sectional views of a somewhat modified form of the invention, showing the parts in different positions.

In the drawing, the casing frame *a* is shown as provided with the usual side grooves in which metal guides *b*, preferably such as are disclosed in my said prior patent, are arranged, which receive the side edge portions of the glass plate *c*, and in which the latter slides vertically, a similar groove being formed in the top of the window opening to receive the top edge portion of the glass.

According to my invention, I provide a strip of resilient sheet metal bent in U-form to provide a bottom portion *d* and two side portions *e* and *f*, which are bent at right angles to the bottom portion, so that said bottom and side portions fit against the bottom and sides respectively of the casing groove, in which the strip is secured, as shown. At or close to the outer edge of the groove, the side portions *e*, *f*, are bent sharply inward at an angle of approximately 45°, forming resilient end portions *g*, *h*, which meet at a short distance from the bottom portion *d*.

The end portion *g* is provided with an outwardly turned lip *i* at its edge, forming a slight concavity on its outer surface into which the end portion *h* extends, so that its edge either engages, or is held in close proximity to the surface of said concavity, when the parts are in normal position, or the glass is lowered out of contact therewith, as shown in Fig. 3.

- 10 When the glass is raised, under normal conditions it will be guided so that its corners will engage the end portions *e*, *f*, practically simultaneously and then on further upward movement the end portions *e*, *f*, 15 will be wedged apart, the resistance to the lifting movement rapidly increasing until the end portion *f* is pushed aside and the top edge of the glass engages the lip *i* in the concave recess, at which point a yieldable abutment is provided which will indicate to the operator that the glass has been 20 lifted to its fullest extent. The glass may be forced up until the end of the lip *i* is moved into engagement with the bottom portion *d*, but usually the suddenly increased resistance will cause the operator to discontinue raising the glass, so that undue strain will not be placed on the lifting means. In this position the end portions *e*, 25 *f* will not only resiliently engage the opposite sides of the glass, so that it will be effectively cushioned laterally, but they will also provide a yieldable resistance to the upward movement of the glass.
- 30 In Figs. 4, 5 and 6, I show a slightly modified form of my invention, in which the bottom and side portions are identical to those already described and also the end portion *e'* and lip *i'*. The end portion *f'* is, however, provided with a laterally bent lip *j* at its inner end, similar to the lip *i*, which is arranged to overlie the lip *i'*, as 35 shown in Fig. 4.
- With this arrangement, when the glass is 40 raised, its edge will first abut with the lip *j*, after it has engaged the end portions *e'*, *f'* and wedged them apart to an extent, as shown in Fig. 5, providing a considerably increased resistance to the lifting of the 45 glass and then if the glass is raised still more, so that it presses aside the end portion *f'*, it will engage the lip *i'*, which will 50 provide a greatly increased resistance, or a slightly yieldable stop for the glass, as indicated in Fig. 6.

I claim:

1. In combination with a window casing having a window glass plate mounted to slide vertically therein, means to receive the upper edge of the glass, when raised to closed position, comprising a strip of resilient sheet metal bent in U-form to provide a bottom, two side portions and resilient end portions extending convergently from said side portions towards said bottom, to provide a resilient support for the glass at each side thereof, one of said end portions having its edge portion bent laterally towards the other to form a lip of less width than the thickness of the glass and arranged for engagement with the edge and adjacent side of the glass successively as it is moved to closed position, to provide a yieldable abutment therefor.

2. In combination with a window casing having a window glass plate mounted to slide vertically therein, means to receive the upper edge of the glass, when raised to closed position, comprising a strip of resilient sheet metal bent in U-form to provide a bottom, two side portions and resilient end portions extending convergently from said side portions towards said bottom, to provide a resilient support for the glass at each side thereof, said end portions each being bent laterally towards the other to form lips arranged for engagement with the edge of the glass to provide yieldable stops therefor as it is moved into engagement therewith.

3. In combination with a window casing having a window glass plate mounted to slide vertically therein, means to receive the upper edge of the glass when raised to closed position comprising a strip of resilient sheet metal bent in U-form to provide a bottom and two side portions, and resilient end portions extending convergently inward from said side portions to provide a resilient support for the glass at each side thereof, said end portions each having a laterally bent lip at its edge, said lips being arranged to overlap each other in position for successive engagement with the upper edge of the glass and to provide successively acting resilient abutments for the glass as it is moved to its closed position.

In testimony whereof I have signed my name to this specification.

EDWIN W. M. BAILEY.
